UNITED STATES PATENT OFFICE

ROBERT W. TRACY, OF TOLEDO, OHIO, ASSIGNOR TO THE DE VILBISS COMPANY, OF TOLEDO, OHIO, A CORPORATION OF OHIO

AIR BRUSH

Application filed January 10, 1929. Serial No. 331,570.

This invention relates to a spraying device of the type commonly known as an air brush, and it is constructed with special reference to its use in the art of spray painting.

5 In spray painting, as the fluid paint leaves the nozzle, there is always a tendency for it to spread or scatter in all directions from the center line of the stream and it is therefore desirable to provide means to flatten the 10 stream so that it may be caused to assume the shape of a fan and so that the paint, as it reaches the object to be painted, will be applied thereto in the form of a thin, flat, uniform sheet. Various devices have heretofore 15 been proposed for flattening the paint stream by means of supplemental air jets directed against the sides thereof, but the operation of such devices has been more or less imperfect because of the great difficulty in maintaining precisely the correct pressure on the 20 supplemental jets or in producing jets of the proper shape and direction to flatten the stream into a sufficiently thin sheet without splitting the same or at least making some 25 portions thereof thinner than other portions.

It is with the above conditions in mind and with the object of overcoming the difficulties mentioned, that the present invention has been perfected.

30 The specific construction of the invention in its present form and the principles of its operation will be explained particularly in connection with the accompanying drawing, the single figure of which represents a central longitudinal section through the discharge end of the spray head.

35 In the spray head in connection with which the invention is illustrated, the body portion 1 is provided with a central passageway 2 through which the paint passes. A liquid nozzle 3 is secured to the body portion at the outlet end of the passageway 2 by means of a union 4. This nozzle 3 has a tapered outlet 5 through which the flow is controlled by 40 means of a needle valve 6.

An air nozzle 7 encompasses the liquid nozzle 3 and is secured to the body 1 by means of a union 8. This air nozzle is so designed as to leave an air chamber 9 surrounding the 45 liquid nozzle 3 and air under pressure is sup-

plied through a passageway 10 in the body 1. The discharge of the air through the annular orifice 11 induces a stream of paint to flow from the outlet 5.

In applying my invention to the spray 55 head above described, oppositely disposed auxiliary air passages 12 lead outwardly from the chamber 9 and each of these passages has two outlets 13 and 14. These outlets 13 and 14 converge toward their mouths and 60 both incline toward the paint laden stream, so that the air streams emitted from the outlets 13 and 14, as shown by the dot and dash lines, merge together before they strike the paint-laden stream and are both flattened out to 65 form a single fan-shaped supplemental jet on each side of the main stream. In this manner the effect of each supplemental jet is softened so that it will not penetrate or scatter the paint stream, and a further effect of 70 the confluence of the two air streams emitted from the outlets 13 and 14 is to spread the jets around the paint stream so that they substantially envelop the same and at the same time flatten it into the shape of a compara- 75 tively thin fan of uniform thickness.

While I have shown and described the invention in connection with one specific type of spray head, it is obvious that the invention is not limited thereto, but may be used in connection with any spray head using compressed air or a similar medium for effecting the discharge of the material stream. It is to be understood, therefore, that the invention includes all such modifications as fall within 80 the scope of the appended claims.

What I claim is:

1. An air brush provided with means for discharging a material laden stream by the use of air under pressure, and means for discharging supplemental air jets against opposite sides of the main stream to flatten the same, the supplemental jet discharge means at each side of the material stream including a plurality of outlets which are in a common 95 plane with the material stream and which converge at such an angle that the streams emitted thereby intersect and form a single fan-shaped air stream before impinging against the main stream. 100

2. In an air brush, means for discharging a material laden stream by the use of air under pressure, and means for discharging supplemental air jets against opposite sides of the main stream to flatten the same, said last means including a set of at least two air discharge orifices at each of opposite sides of the main stream with the lines of discharge of the outer orifices of the two sets converging and intersecting at a point on the axis of the main stream and with the lines of discharge of the next orifice of each set intersecting the line of discharge of the outer orifice of the respective set at a point spaced from but adjacent to the main stream whereby the supplemental air streams of each set merge and form fan-like air streams before striking the main stream.

In testimony whereof I have hereunto signed my name to this specification.

ROBERT W. TRACY.
